POULTRY SCALDING MACHINE

Harley C. Truex and Leslie O. Brown,
Columbus, Ind.

Application May 13, 1929, Serial No. 362,640

1 Claim. (Cl. 17—11)

This invention relates to new and useful improvements in machines for scalding poultry and more particularly to a machine on which the poultry is killed and immediately passed through the scalding operation.

The principal object of this invention is to provide a machine of the character mentioned which, in use, will eliminate the necessity of requiring the services of three or four men for operating the machine as is now required in machines for this purpose with substantially the same capacity.

Another important object of the invention is to provide a machine for scalding poultry whereon the poultry may be first suspended, then killed and passed through the scalding operation, so that each piece of poultry will be treated uniformly.

Another object of the invention is to provide a machine of the character mentioned which will be semi-automatic in operation and wherein the parts will be positive acting and will not be susceptible to the development of frequent defects.

These and numerous other important objects of the invention will become more apparent to the reader after considering the invention as described and claimed hereinafter.

In the drawings:

Figure 1 represents a side elevation of the machine.

Figure 2 represents a top plan view of the machine.

Figure 3 represents a vertical transverse sectional view looking toward one end of the machine.

Figure 4 represents a vertical transverse sectional view looking toward the opposite end of the machine.

Figure 5 is a side elevation of a carriage for supporting a piece of poultry.

Figure 6 represents an edge elevation of the carriage for supporting poultry.

Figure 7 represents a vertical sectional view through one of the transfer wheels of the machine.

Referring to the drawings, wherein like numerals designate like parts, it will be seen that the present invention includes an elongated tank 5 of predetermined width, depth and extent and having substantially one-half portion of its bottom declining inwardly at one end as at 6. Numeral 7 denotes the water inlet, while the steam inlet is designated by numeral 8 and a drain pipe situated below the aforementioned inlet is denoted by 9.

The tank 5 is supported at its intermediacy by

legs 10, while legs 11 at the corners of the tank support the same at its ends.

An endless track, generally referred to by numeral 12 is supported in overlying respect to the tank and is of an encompassing area extending beyond the horizontal confines of the tank in all directions. The track is disposed horizontally as at 13 from a point 14 to the point 15 to provide a working place for the operator generally called the "sticker or filler" who bleeds the fowl prior to the dipping of same in the tank, (see Figure 2) where the track bends as at 16 and from the point 17 dips downwardly to the point 18 (see Fig. 3), in close overlying proximity to the tank 5 and extends longitudinally thereof to the point 19. The portion of the track between the points 18 and 19 is designated by numeral 20 and is substantially parallel to the horizontal portion of the track denoted by numeral 19 and this portion 20 is also parallel and co-planar with the portion 21 which continues the track from the point 19 around the curved portion 22, to the point 23, where it inclines upwardly to the point 24, from where it swerves outwardly beyond the sides of the tank (see Figure 3) and gradually declines on the curve 25 to merge with the elongated inclined portion 26 to the point 27 where it starts to incline sharply upwardly along the portion 28 to the curve 29 where it merges with the horizontally declining portion 30 connecting the curved portion 29 with the starting point 14.

At regular intervals, the track is supported by suitable braces 31. A pair of posts 32—32 extend upwardly at opposite sides of the tank and adjacent the end thereof for generally supporting the vertically spaced drive shafts 33 and 34. The upper drive shaft 33 projects beyond one post 32, and is equipped with a sprocket wheel 35, while the lower shaft 34 projects beyond the opposite post 32 and is equipped with a sprocket wheel 36. Pulleys 37 on the aforementioned drive shafts are connected by suitable belts 38 to a power source.

Sprockets 39 and 40 are secured to the shaft 34 in spaced relation and at opposite sides of the geared transmission 41, for actuating the counter-shaft 42. The horizontally disposed sprocket 43 is secured to the lower end of the counter shaft 42 in the manner shown in Figure 4. The wheel shown at 43 is provided with a plurality of radiating arms 44.

Secured to the same end of the tank 5 is an upright 45 which extends above the adjacent post 42 and has its upper end curved downwardly and outwardly as at 46.

A shaft 47 is journaled between the end of the

upright and its adjacent parallel portion and is equipped with a sprocket 48. A bracket 49 at the adjacent side of the tank 5 supports a shaft 50 which has a sprocket 51 keyed thereto. An endless sprocket chain 52 is trained over the sprocket wheels 48 and 51 and is adapted to be driven by the sprocket 36 meshing therewith.

The chain 52 carries a plurality of lugs 53 secured to its outer side at equally spaced intervals. 10 As is clearly shown in Figure 1, the chain 52 has its lower flight disposed in substantial parallelism with respect to the inclined portion 28 of the track. At the same side of the tank 5 is secured a pair of uprights 54—54, one of which is substantially shorter than the other while an elongated bar 55 is secured in the inclined position shown in Figure 1, to the upper ends of the uprights 54—54, and at its lower end to the tank as at 56. The bar 55 serves as a brace for the uprights, which 15 uprights support stem 57 and 58, the latter being lower than the former, but both extending transversely of the tank and being supported by corresponding posts 59 and 60 secured to the opposite side of the tank. The upper shaft 57 carries 20 sprockets 60' and 61, while the lower shaft carries sprockets 62, and 63. An endless chain 64 is trained over the sprockets 60', 62 and 40, the latter on shaft 34, (see Figure 4) and the same is provided with a multiplicity of outwardly projecting lugs 65, at equally spaced intervals. The sprockets 61, 63 and 39, the latter on shaft 34, are connected by a chain 66 disposed over the portion 20 of the track, while the chain 64 is disposed over the portion 21 of the track. A 25 sprocket 67 on the shaft 57 is located beyond the horizontal confines of the track 5, while a chain 68 is trained over the pulleys 57 and 35, (the latter on shaft 34).

Lugs 68 are provided on the outside of the 40 68 is disposed completely above the horizontal chain 68 at equally spaced intervals. The chain portion 13 of the track. A bracket 70 supports a vertical shaft 71, which is inter-geared as at 72 with the shaft 57. The shaft 71 carries a 45 wheel 73, from which radially project a plurality of arms 74. The wheel 73 is disposed substantially concentrically with the curved portion 16 of the track in a manner so that its arms 74 will sweep over said curved portion of the track 50 in substantially the same manner as will the arm 44 of the wheel 43 sweep over the curved portion 20 of the track. A plurality of such carriers, as are shown in Figures 5 and 6 will be employed for use in conjunction with the present 55 machine. Each carrier consists of a boss 75 having its upper portion bent outwardly as at 76 and downwardly as at 77. A pin 78 interposed between the downwardly bent portion 77 and the adjacent parallel portion of the bar 75 supports 60 a grooved roller 79. The bar 75 at its upper portion is substantially triangular shaped as shown in Figure 5 and at the lower converging portion thereof a bracket 80 is secured for supporting a rotatable grooved roller 81. The upper rollers 79 are adapted to ride upon the top edge of the track 12, while the lower roller 81 is adapted to engage the lower edge of the track.

The lower end of the bar 75 is twisted as at 82 and a plate 83 is secured transversely thereon. This plate 83 is provided with upwardly extending and spaced fingers 84 which are disposed in oblique relation with respect to the bar 75. Between the outermost fingers 84 and the innermost finger are to be positioned the legs of a fowl.

It will thus be seen that when a carrier is positioned on the portion 13 of the track which is beyond the side of the tank, a fowl suspended 10 therefrom may be stuck for bleeding purposes and the carrier then engaged with the chain 68 which will carry it to the wheel 73 from where it will pass down the incline to the horizontal stretch 20, where the operation of scalding the 15 fowl is carried on. Owing to the fact that some fowls do not require as long periods as others for bleeding, the sticker or filler may put his "stick" at such places along the stretch of tracks between points 14 and 15 as experimenting may 20 prove to be best suited to the weight and size of each fowl. The carrier finally comes to the portion 26 of the track where the fowl is removed by another operator known as the "picker" or fowl remover. The fowls are removed in the 25 order in which they pass through the tanks. After the fowl has been removed from a carrier, the latter is engaged with the conveyor chain 52 moves up the incline 28 to its starting position for refilling section 29 of the track where a third 30 operator attaches another fowl to the carrier. A plurality of these carriers may be arranged on the portion 29 of the track and moved on to the sticker in successive order.

While the foregoing description has been in 35 definite terms it is to be understood that numerous changes in the specific shape, size and materials may be resorted to, without departing from the spirit and scope of the invention as claimed hereinafter.

What is claimed is:

A poultry scalding machine comprising a hot water tank, an endless track arranged horizontally above said tank, said track having an outer U-shaped portion disposed without the confines 45 of the tank, and an inner U-shaped portion overlying the surface of said tank, with the sides of said inner U-shaped track portion lying in vertical planes substantially parallel to the sides of the outer U-shaped track portion, and also at 50 the open end of the U being bent upwardly and reversely to merge with the sides of the outer U-shaped track portion exteriorly of the tank and adjacent one end of the latter; a fowl carrier movable on said track, means arranged adjacent to portions of said track for moving the fowl carrier, said means including endless chains having lugs thereon to engage the fowl carrier for 55 moving the latter over elongated portions of said track, and wheels with arms engaging the fowl carrier to move the latter around the curves at the ends of the track; and means for supporting 60 said fowl carrier-impelling chains, wheels, and track on the tank.

HARLEY C. TRUEX.
